UNITED STATES PATENT OFFICE.

JOSEPH W. ROTH, OF NEW BRUNSWICK, NEW JERSEY.

SLED.

Application filed August 13, 1927. Serial No. 212,732.

This invention aims to provide novel means whereby a "scooter" or toy wagon may be provided with runners, it being possible, thus, to provide a toy which can be 5 used in the winter-time, by taking off the wheels and replacing them with runners.

It is within the province of the disclosure to improve generally and to enhance the utility of devices of that type to which the 10 invention appertains.

With the above and other objects in view which will appear as the description proceeds, the invention resides in the combination and arrangement of parts and in the 15 details of construction hereinafter described and claimed, it being understood that changes in the precise embodiment of the invention herein disclosed, may be made within the scope of what is claimed, without 20 departing from the spirit of the invention.

In the drawings:—

Figure 1 shows in side elevation, a device constructed in accordance with the invention;

25 Figure 2 is a top plan of the structure shown in Figure 1;

Figure 3 is a perspective showing one of the brackets;

30 Figure 4 is a front elevation, parts being broken away;

Figure 5 is a cross section on the line 5—5 of Figure 1;

Figure 6 is a perspective view showing one form of runner;

35 Figure 7 is a perspective view showing another form of runner.

The numeral 1 marks the body of a scooter or toy wagon, of the kind which, generally, is propelled when the operator stands with 40 one foot on the vehicle and kicks the other foot against the ground, the vehicle being used, sometimes, for coasting. Although the device forming the subject matter of this application may be used on vehicles of 45 widely different sorts, a scooter of the kind mentioned has been selected as illustrative. The body 1 of the vehicle comprises bars 2 on which a platform 3 is mounted. A loop-shaped prop 4 is pivoted at 5 to the 50 rear end of the body 1. When the wheels are on the body 1, the prop 4 is turned down to support the vehicle in an upright position, in a way which will be readily understood. A standard 7 is pivoted at 8 to the 55 upturned forward end 9 of the body 1 and

is equipped at its upper end with a steering handle 10. The standard 7 preferably is made up of parallel bars 11, as shown in the drawings.

From such a vehicle, or a similar vehicle, 60 the wheels are removed, and then recourse is had to parts which will now be described.

For the convenience and comfort of the operator, a seat 14 is supported by legs 15 from the platform 3. The numeral 16

marks the rear runner, the upturned forward end 17 of which carries a cross member 18 that bears against the under edges of the bars 2 of the body 1. Above the bars

2 is located a clamp bar 19, and the clamp bar is connected with the cross member 18 by draw bolts 20, the forward end of the runner 16, thus, being held securely but firmly on the body 1. The runner 16 pref-

erably is T-shaped in cross section, and to 70 the upstanding flange of the runner is se-

cured a post 21 carrying at its upper end a cross member 22 that bears against the lower edges of the bars 2 at the rear end of the body 1. Above the rear end of the bars 2

is located a clamp bar 23, and draw bolts 24 connect the bar 23 with the cross mem-

ber 22, the upper end of the post 21, thus, being held securely but releasably on the rear edge of the body 1. The runner 16 has 80

an upwardly projecting arm 25 at its rear end, carrying a cross piece 26. The prop 4 rests on the cross piece 26 and because the prop 4 is of angular form, as disclosed clear-

ly in Figure 1, it may be used to hold the 90 packages and the like against sliding off the rear end of the body 1.

An axle 25 is mounted removably in open- 95 ings in the lower ends of the bars 11 which make up the standard 7. Angle brackets 28

are provided, each bracket comprising a trough-shaped body 29 and a depending arm 30 having an outstanding flange 31. There are notches 32 in the edges of the body 29. The arm 30 is provided with an 100 opening 33. The ends of the axle 27 rest in the trough-shaped body 29 of the angle brackets 28.

Clamp plates 34 are mounted upon the ends of the axle 27. U bolts 35 surround the bodies 29 of the angle brackets 105 28 and the arms of the U bolts are disposed in the notches 32. The arms of the U bolts 35 extend upwardly through the clamp plates 34, and the nuts on the U bolts bear

110 on the clamp plate 34. By the construc-

tion above described, the angle brackets 28 are mounted firmly but removably on the ends of the axle 27, with the arms 30 of the angle brackets extending downwardly.

5 Loop-shaped forward runners 36 are provided, the upper, forward corners of the runners being designated by the numeral 37. The runners 36 include alined upper arms 38, the inner ends of which are spaced apart, as shown in Figure 6, and provided with upstanding fingers 39. The inner ends of the arms 38 rest upon the flange 31 of the angle bracket 28, and against the arm of the angle bracket, the fingers 39 extending upwardly along the outer surface of the arm 30. Around the fingers 39 is placed a clamp plate 40 which is U-shaped in top plan, as shown in Figure 2. A securing device, such as a bolt, is extended through the opening 33 in the arm 30 of the angle bracket 28, and through the clamp plate 40, the nut on the securing element 41 engaging the clamp-plate 40. The construction at this point is such that the intermediate upper portion of the runner 36 will be held securely but detachably on the end of the axle 27.

10 U-shaped anchor plates 42 extend across the angles 37 of the runners 36, and are located on the outer sides of the runners. upwardly and rearwardly extended braces 43 are provided. The braces 43 have downwardly extended ends 44 bearing against the washers 45 that are located in 15 the angles 37 of the runners, in engagement with the anchor plates 42. Securing elements 46, such as bolts, extend through the anchor plates 42, through the washers 45, and through the depending ends 44 of the braces 43, the braces thus being held securely but detachably, at their lower ends, on the runners 36 at the upper forward corners thereof. The braces 43 have their upper ends 47 crossed upon each other. The ends 47 of the braces 43 are attached by a bolt 48 to a cross bar 49 which bears against the forward edges of the constituent members 11 of the standard 7. A U bolt 50 is disposed around the standard 7 and passes through the braces 43. The braces, thus, are secured removably to the steering standard 7.

15 The operator may stand on the platform 3 or occupy the seat 14, and, through the instrumentality of the handle 10, the standard 7 may be turned on its pivotal mounting 8, thereby to impart movement to the axle 27, and from the axle 27 to the runners 36, so that a steering of the device may be brought about.

20 The construction is simple, but the device shown affords a means whereby a wheel-mounted vehicle may be turned into a sled at the will of an operator.

25 In the form shown in Figure 7, the run-

ner is denoted by the numeral 51 and its arms are shown at 52, the fingers 53 projecting inwardly at right angles to the plane defined by the runner, instead of being located in the same plane with the runner as is the case in Figure 6. When the runner shown in Fig. 7 is used, the angle bracket 28 is done away with, and the U-bolts 35 are engaged directly with the fingers 53.

30 What is claimed is:—

1. In a device of the class described, a body, means for supporting the rear end of the body, a steering standard pivoted on the forward end of the body, an axle mounted on the standard, angle brackets comprising bodies and depending parts, said parts being supplied with outstanding flanges, means for securing the bodies of the angle brackets to the ends of the axle, runners including upper arms having upstanding fingers, the arms resting on the flange, and clamping means mounted on the depending parts of the angle brackets and holding the fingers thereagainst.

35 2. In a device of the class described, a body, means for supporting the rear end of the body, a steering standard pivoted on the forward end of the body, an axle mounted on the standard, angle brackets comprising bodies and depending arms, means for securing the bodies of the angle brackets to the ends of the axle, runners, and means for securing the runners to the arms of the angle brackets.

40 3. In a device of the class described, a body, means for supporting the rear end of the body, a steering standard pivoted on the forward end of the body, an axle mounted on the standard, angle brackets comprising trough-shaped bodies, and depending parts, said parts being supplied with outstanding flanges, the ends of the axle being received in the trough-shaped bodies, means for holding the ends of the axle, in the trough-shaped bodies, runners including upper arms resting on the flange, and means for clamping the arms of the runners on the depending parts of the angle brackets.

45 4. In a device of the class described, a body provided at its rear end with a pivotally mounted member, a runner, means for securing the forward end of the runner to the body, means for securing the intermediate portion of the runner to the body, and an upwardly prolonged arm on the rear end of the runner and constituting a support for the pivotally mounted member.

50 5. In a device of the class described, a body, a single runner mounted on the rear end of the body, a standard pivotally carried by the forward end of the body and under the control of an operator, for steering, an axle on the lower end of the standard, runners, and means for connecting the runners with the ends of the axle.

6. In a device of the class described, a body, a single runner mounted on the rear end of the body, a standard pivotally mounted on the forward end of the body, for steering, an axle carried by the lower end of the standard, horizontally spaced runners, means for mounting the runners on the ends

of the axle, braces connected to the forward ends of the runners, and means for connecting the braces with the standard. ¹⁰

In testimony that I claim the foregoing as my own, I have hereto affixed my signature.

JOSEPH W. ROTH.
